RADIO TUNING APPARATUS

Edmund A. Gschwind, Chicago, Ill., assignor to
 Stewart-Warner Corporation, Chicago, Ill., a
 corporation of Virginia

Application October 7, 1940, Serial No. 360,021

10 Claims. (Cl. 74—10)

This invention relates to new and improved push button tuning mechanism, and more particularly to tuning mechanism of this character especially adapted for use with radio receiving sets.

The present commercial type of radio broadcast receiver comprises a tuning element, such as a variable condenser, which requires very accurate adjustment to tune in a desired station properly and with good tone quality. A push button tuner for such sets must therefore be capable of rotating or otherwise moving the associated tuning element with a great degree of accuracy and with uniformity of movement in repeated use. Cost limitations in commercial practice require a tuner to be produced in quantities at a minimum of expense. This requires in turn that the parts of the tuner be capable of production without working to extremely close tolerances. It also requires that the assembly and adjustment of the parts be simple and that parts be interchangeable.

It is an object of the present invention to provide a new and improved push button tuner which is simple in design and operation and adapted for commercial production.

It is a further object to provide a construction in which the push rods or push button slides are independent of the mechanism for rotating the tuning element.

It is also an object to provide a construction in which separately supported actuating members are interposed between the push rods and the rotary cam shaft connected to the tuning element.

It is an additional object to provide a construction with independently supported and coacting operating levers actuated jointly by the push rods.

It is another object to provide a construction which comprises parts which do not require close dimensional tolerances to operate accurately and uniformly.

Other further objects will appear as the description proceeds.

I have shown certain preferred embodiments of my invention in the accompanying drawings, in which—

Figure 1 is a plan view of the tuning apparatus and the associated tuning element;

Figure 2 is a view of the construction of Figure 1 taken on line 2—2 of Figure 1; and

Figure 3 is a fragmentary vertical section illustrating the construction.

In the drawings, the frame 11 supports the tun-

ing element 12, which is shown in this case as a two gang condenser. The frame 11 also supports the cam shaft 13 which supports a plurality of sector-shaped cams 14, as shown in Figure 3. A manual drive disc 15 is supported on stub shaft 16 in a bracket 17 secured to the front of the frame 11. This disc 15 drives a gear 18 which in turn drives gear 19 carried on stub shaft 20 supported by frame 11. Shaft 20 further carries gear 21 which drives gear 22 carried on stub shaft 23 extending from frame 11. This shaft 23 carries the small gear 24 meshing with gear 25, which is secured to the shaft 26. This shaft 26 is in alignment with the cam shaft 13 and is connected 15 therewith by means of the magnetic clutch 27.

The opposite end of shaft 13 carries a gear section 28 which meshes with the gear 29 secured to the shaft 30 of the condenser 12. This shaft 30 also carries the cable drum 31 which drives the dial cable 32. This cable 32 passes around idler pulleys 33, 34 and 35 and serves to move the pointer 36 above the dial strip 37. The cam shaft 13 carries the clamping mechanism 38, by means of which the cam sectors 14 may be clamped to rotate with the shaft 13 or may be released for adjustment. This clamping mechanism is conventional and need not be further described since it forms no part of the present invention.

The frame 11 also carries the upper lever pivot shaft 39 upon which are pivoted a plurality of levers 40. These levers are each formed of two spaced members joined at an intermediate point by the drive member 41 and at their ends by the cam contact member 42. The lower lever pivot shaft 43 is carried by the frame 11 below the cam shaft 13 and carries a plurality of levers 44. These levers 44 are also formed of two spaced members, these members being joined by cam drive member 45. The lower levers 44 are provided with an arcuate surface 46 to be engaged by the drive members 41 carried by the upper levers 40. It is to be noted that the drive member 41 is provided with a reduced portion 47 so that it only engages one side of the lower cam lever 44. This prevents any variable movement of the parts due to imperfect alignment of members, as might occur if both sides of the lever 44 were engaged by the cylindrical member 41. This, therefore, aids in making the construction accurate in operation without the necessity for extremely close manufacturing tolerances.

The frame 11 is provided with an intermediate cross piece 48 having a plurality of slots to receive the push button slides 49. These slides pass through similar slots in the front cross frame 55

member 50 and are provided with springs 51 engaging the member 50 and having their opposite ends extending through openings in the slide so as to maintain the slide normally at its outer limit of movement. The slide 49 is shown as provided with the push button 52, but it may be operated by any desired means.

The frame 11 carries the insulating switch base 53, as best shown in Figure 2, which base supports the spaced switch contacts 54 and 55. The contact 55 has an extended upper portion carrying a disc 56 formed of insulation. The switch is connected in circuit with the magnetic clutch 27. This magnetic clutch is normally in connecting or clutching position. When current is passed through it, it is declutched. Consequently when switch contacts 54 and 55 are in engagement the clutch is out of operation. The switch operating shaft 57 has a crank portion 58 extending under the slides 49 and normally fitting in notches 59 in these slides. The end of the shaft 57 is provided with an upwardly extending portion 60, adapted to engage the insulating disc 56 to close the switch when the shaft is rotated in clockwise direction, as seen in Figures 2 and 3. It will be seen that movement of any push button slide 49 inwardly will serve to move the notch 59 of the slide away from the portion 58 of the shaft 57, and that the shaft 57 will be rocked in a clockwise direction to close the switch. The inner end of each slide 49 is provided with an elongated foot portion 61 adapted to engage the operating member 41 of the adjacent upper pivot lever 40.

The upper levers 40 are held at their limit of clockwise movement by springs 63 which have one end secured to a lever 40 and the opposite end secured to the frame member 64. The movement of the levers in this direction is limited by the contact of the intermediate drive member 41 with the foot portion 61 of the associated slide 49. The lower levers 44 are held at their counterclockwise limit of movement by similar springs 65, the opposite ends of which are secured to the rear portion of the frame 11. The movement of these levers in this direction is limited by the contact of the arcuate surface 46 with the drive member 41 of the associated upper lever 40.

In the operation of the device, in order to set up the cam actuated by any given push button for a desired station, the clamping of the cam is released by means of mechanism 38. The push button 52 associated with the cam being set up is then thrust inwardly to its limit of movement which, by pressure against the drive member 41 of the upper lever 40 transmitted through the drive member 41 to the lower lever 44, forces the two levers inwardly about their pivots so that the cam contact members 42 and 45, respectively, engage the opposite faces of the associated cam 14. If the cam 14 is in an intermediate position, one or the other of the members 42 and 45 will first engage the cam and thrust it around its shaft 13 until the other of the two members is also solidly seated against it. With the cam held in this position the tuning assembly is tuned to bring in the desired station, after which the cam will again be clamped in locked relation to shaft 13 by means of mechanism 38. When the button is released, the parts will return to the position shown in Figure 3. A plurality of cams may be set up during one release of the cams, and the adjustment of any cam may be readily changed in the manner described whenever desired.

During the operation of the tuning assembly for tuning the radio set after the cams are properly set up, any station for which a push button is adjusted may be instantly tuned in by pushing the designated button inwardly to its limit of movement. The initial operation of this movement serves to rock the shaft 57 and by closing switch 53 disconnects the manual tuning mechanism by declutching the magnetic clutch 27. Consequently the shaft 13 rotates easily upon pressure against the cam 14 by the associated lever drive members 42 and 45. It will be noted that the indicating dial mechanism is connected to the tuning element 12 so that the dial will be moved by push button tuning and show the relative position of the tuner. The tuning assembly is always instantly adjusted for manual tuning, which is accomplished by means of the manual drive disc 15 and its associated gear train connecting it to the shaft 13 through the magnetic clutch 27.

While I have shown certain preferred embodiments of my invention, these are to be understood to be illustrative only, as it is capable of variation to meet differing conditions and requirements. I contemplate, therefore, such changes and modifications as come within the spirit and scope of the appended claims.

What is claimed is:

1. Radio tuning apparatus comprising a tuning element, a cam shaft having a driving connection with the tuning element, a cam adjustably carried by the cam shaft, said cam having a pair of cam surfaces, a pair of levers pivotally supported adjacent the cam, each lever having means adapted to coact with one of the pair of cam surfaces, and means for swinging the levers about their pivots to cause coaction of said means with the cam to rotate the cam shaft.

2. Radio tuning apparatus comprising a tuning element, a cam shaft having a driving connection with the tuning element, a cam adjustably carried by the cam shaft, said cam having a pair of cam surfaces, a pair of levers pivotally supported upon opposite sides of the cam, each lever having means adapted to coact with one of the pair of cam surfaces, and means for swinging the levers about their pivots to cause coaction of said means with the cam to rotate the cam shaft.

3. Radio tuning apparatus comprising a tuning element, a cam shaft having a driving connection with the tuning element, a cam adjustably carried by the cam shaft, said cam having a pair of cam surfaces, a pair of levers pivotally supported adjacent the cam, each lever having means adapted to coact with one of the pair of cam surfaces, the levers having interengaging portions whereby movement of one lever toward the cam causes simultaneous movement of the other lever in the same direction, and means for moving said levers to cause coaction of the lever means and cam to rotate the cam shaft.

4. Radio tuning apparatus comprising a tuning element, a cam shaft having a driving connection with the tuning element, a cam adjustably carried by the cam shaft, said cam having a pair of cam surfaces, a pair of levers pivotally supported adjacent the cam, each lever having means adapted to coact with one of the pair of cam surfaces, the levers overlapping each other with the outer lever having means engaging the inner lever, means for swinging the outer lever toward the cam and thereby swinging the inner lever in the same direction and causing the cam

engaging means on the levers to engage the cam to rotate the shaft.

5. Radio tuning apparatus comprising a tuning element, a cam shaft having a driving connection with the tuning element, a cam adjustably carried by the cam shaft, said cam having a pair of cam surfaces, a pair of levers pivotally supported upon opposite sides of the cam shaft, each lever having means adapted to coact with one of the pair of cam surfaces, the levers overlapping to engage cam surfaces on the opposite side of the cam shaft to the lever pivot, and means for simultaneously moving the levers about their pivots to cause coaction of the lever means with the cam surfaces to rotate the cam shaft.

6. Radio tuning apparatus comprising a tuning element, a cam shaft having a driving connection with the tuning element, a cam adjustably carried by the cam shaft, said cam having a pair of cam surfaces, a pair of levers pivotally supported upon opposite sides of the cam shaft, each lever having means adapted to coact with one of the pair of cam surfaces, the levers overlapping to engage cam surfaces on the opposite side of the cam shaft to the lever pivot, means on the outer lever to engage and move the inner lever, and means for moving the outer lever whereby the lever means of the two levers are caused to coact with the respective cam surfaces to rotate the cam shaft.

7. Radio tuning apparatus comprising a tuning element, a cam shaft having a driving connection with the tuning element, a cam adjustably carried by the cam shaft, said cam having a pair of cam surfaces, a pair of levers pivotally supported adjacent the cam, each lever having means adapted to coact with one of the pair of cam surfaces, and an independently mounted sliding member adapted to swing the levers about their pivots to cause coaction of the lever means with the cam to rotate the cam shaft.

8. Radio tuning apparatus comprising a tuning element, a cam shaft having a driving connection with the tuning element, a cam adjust-

ably carried by the cam shaft, said cam having a pair of cam surfaces, a pair of levers pivotally supported adjacent the cam, each lever having means adapted to coact with one of the pair of cam surfaces, the levers having interengaging portions whereby movement of one lever toward the cam causes simultaneous movement of the other lever in the same direction, and an independently mounted sliding member for engaging the first lever to swing both levers to cause coaction of the lever means and cam to rotate the cam shaft.

9. Radio tuning apparatus comprising a tuning element, a cam shaft having a driving connection with the tuning element, a cam adjustably carried by the cam shaft, said cam having a pair of cam surfaces, a pair of levers pivotally supported upon opposite sides of the cam shaft, each lever having means adapted to coact with one of the pair of cam surfaces, the levers overlapping to engage cam surfaces on the opposite side of the cam shaft to the lever pivot, and an independently mounted sliding member for simultaneously swinging the levers about their pivots to cause coaction of the lever means with the cam surfaces to rotate the shaft.

10. Radio tuning apparatus comprising a tuning element, a cam shaft having a driving connection with the tuning element, a cam adjustably carried by the cam shaft, said cam having a pair of cam surfaces, a pair of levers pivotally supported upon opposite sides of the cam shaft, each lever having means adapted to coact with one of the pair of cam surfaces, the levers overlapping to engage cam surfaces on the opposite side of the cam shaft to the lever pivot, means on the outer lever to engage and move the inner lever, and a sliding member having a foot engaging the outer lever whereby an inward movement of the sliding member swings both levers simultaneously to cause the lever means of the two levers to coact with the respective cam surfaces to rotate the cam shaft.
